COMBINATOR HEAD OR HOMOGENIZER

John Marco, Philadelphia, Pa., assignor to Marco Company, Inc., Philadelphia, Pa., a corporation of Pennsylvania

Application July 29, 1939, Serial No. 287,422

3 Claims. (Cl. 252—359)

This invention relates to new and useful improvements in homogenizer or emulsor valves and is particularly applicable to the pump and homogenizer structure illustrated in my pending application Serial No. 235,509 and interchangeable with parts and structure illustrated in my co-pending applications Serial Numbers 271,785 and 271,786, titled, respectively, Grinder and emulsor valve and Grinder, disintegrator, emulsor or the like, it being the primary object of the invention to provide a simple and efficient structure for the homogenization or emulsification of certain materials.

One of the essential objects of the invention resides in the provision of an improved homogenizing valve, self-aligning with respect to its seat and which is non-rotatable when effectively positioned.

Still another object of the invention resides in the provision of an homogenizing construction in which material is fed through the medium of a spiral shaft to an homogenizer valve firmly seated with means on the seat cooperating with portions of the valve to spray the material being treated in the homogenizing chamber.

A still further object of the invention resides in providing a seat for the homogenizer valve provided with an annular groove so arranged with respect to the homogenizer valve, provided in turn with an offset adjacent the effective end thereof, as to cause material fed through the valve to contact the walls of said groove and offset and be sprayed into the homogenizing chamber.

A still further object resides in providing a structure which is capable of ready and simple adjustment or assembly, as well as disassembly, to be interchangeable with parts used on my improved pump structure as illustrated in copending application Serial No. 235,509, as aforesaid, according to the particular material or materials being treated, and a further object resides in the provision of a device which is simple and durable in construction, inexpensive to manufacture and extremely efficient in use.

With these and numerous other objects in view, my invention consists in the novel features of construction, combination and arrangement of parts, as will be hereinafter referred to and more particularly pointed out in the specification and claims.

In the accompanying drawing, forming part of this application,

Figure 1 is a vertical section through my improved emulsor or homogenizer structure attached 55

to a pump, with parts of the latter being shown in elevation.

Figure 2 is a front elevation thereof with parts broken away and parts in section, and

Figure 3 is a side elevation of my complete pump structure with this improved emulsor or homogenizing structure applied thereto.

In my copending application Serial No. 235,509, I have shown a combined pump and homogenizer construction and in my copending application Serial Numbers 271,785 and 271,786, I have shown various types of grinders and emulsors or disintegrators for interchangeable use in connection with said pump structure, according to the materials being treated or the results desired. My present application contemplates a new and improved emulsor or homogenizer valve construction capable of interchangeable connection with the pump structure shown in my copending applications aforesaid. This particular type of homogenizer or emulsor valve structure is used when certain particular materials are being treated and certain results desired.

In describing the device, I shall refer to the drawing in which similar reference characters designate corresponding parts throughout the several views and in which the numeral 1 designates generally the forward end of a pump structure, the details of which are immaterial insofar as this present invention is concerned, since the same is fully described and covered in one of the aforesaid pending applications. For convenience, however, I may state that the numeral 2 designates a rotor housing to which is applied a header plate 3 over which is applied the cover plate 4, all of the parts being secured to the pump body by means of the stud bolts 5.

The cover plate 4 is provided with a tubular axial extension 6 which terminates in an outer head plate or disk 7 and projecting through said portions 6 and 7 to a point beyond the outer face of the latter is a shaft 8 provided with the spiral grooves 9, through the medium of which the material being treated is fed from the pump structure to the homogenizer or emulsor structure.

Up to this point, it will be seen that the structure is quite similar or the same as that shown and described in my copending application for Grinder, disintegrator, emulsor or the like, Serial No. 271,786, but from this structure on, there is a slight difference, the parts being interchangeable with those used in the aforesaid copending application.

Applied to the outer face of the outer head plate 7 of the cover plate is a plate 10 which

I designate as the homogenizer seat plate, the same being provided with a hollow extension 11 into which extends the outer end of the feed shaft 8. This hollow extension 11 is provided with an internal annular flange 12 leaving at the end of the extension a restricted opening 13 through which the materials being treated are fed from the shaft 8. The outer face of this flange 12 constitutes a seat proper for my improved homogenizer valve and said face is provided with an annular groove 14. Abutting the homogenizer valve seat is the homogenizer or emulsor valve 15 which is a solid substantially cylindrical element provided at its effective end with a central conical extension 16 entering the opening 13 of the valve seat. The conical extension 16 at its base is somewhat grooved as shown at 17 so that the materials fed against the cone-shaped portion may be directed arcuately between the faces of the valve and the seat proper. The outer periphery of the valve 15, at its effective end, is offset to provide a shoulder 18 and this shoulder is curved or arcuately formed at its inner end. The effective end of the valve 15 has its diameter just greater than the inner diameter of the groove 14 of the valve seat and the curved portion of the shoulder 18 of the valve is opposite the annular groove 14 so that as the material being treated is fed between the valve and the valve seat proper, the same is caused to enter the annular groove 14 and is directed arcuately toward the curved portion of the shoulder 18 and in turn sprayed from the latter into the homogenizing chamber which, for convenience, I have designated 19.

Applied to the homogenizer seat plate 10 and surrounding the homogenizer valve and seat proper is the housing 20 which forms the homogenizer chamber which is provided with the outlet port 22. The inlet through which material is fed to the pump is shown at 21.

Applied to the outer face of the housing 20 is a seal plate 23 to which is in turn applied the cover plate 24, all of these parts, including the homogenizer seat plate 10 being secured to the outer head plate 1 through the medium of the stud bolts 25. Between the seal plate 23 and cover plate 24 at the inner periphery thereof, is the seal 26, which surrounds the substantially cylindrical homogenizer valve 15.

The cover plate 24 is also provided with a tubular extension 27 through which the homogenizer valve 15 extends and the outer periphery of said tubular extension at the outer end thereof is threaded to receive the internally threaded portion of an adjusting cap 28. The outer end portion of the homogenizer or emulsor valve 15 is somewhat hollowed out and the innermost walls of the hollowed portion are beveled to form a seat for a self-aligning disk or spacer 29. Interposed between the self-aligning disk 29 and the inner portion of the cap 28 is a thrust bearing 30 and a hand bar 31 is applied to the outer end of the cap 28 to enable the latter to be readily adjusted to proper position to turn on the thrust bearing against the alining disk or spacer 29. Through the medium of this cap 28, thrust bearing 30 and disk 29, the valve 15 becomes self-aligning and there is uniform alinement of the valve and seat abutment. No spring tension is required for this valve and the latter will abut snugly to the seat at all times and effectively carry out the purpose for which the same is designed. The material being treated is obviously homogenized or emulsified through

its projection between the valve and the seat but further homogenization and emulsification become effected through the medium of the annular groove and shoulder structure on the seat and valve, respectively, as aforesaid.

A dial 32 is applied to the outer face of the cover plate 24 and a pointer 33 secured to the inner end of the cap 28 for notation of the adjustment of said cap, just as is shown and described in my copending application Serial No. 271,786.

From the foregoing description of the construction of my improved device, the operation thereof will be readily understood and it will be seen that I have provided a comparatively simple, inexpensive and efficient means for carrying out the purposes and objects of the invention. It will be seen that the structure is such that the various elements may be quickly and readily removed at the will of the operator for purposes of cleansing, as is necessary and required under the law where foods and drugs are being processed.

It will be further seen that the device is capable of interchangeability with parts and structure of the apparatus in my copending applications, as aforesaid, so that this particular homogenizer valve structure may be used as alternative structure with other homogenizer or disintegrator apparatus used in association with my pump structure now known to the trade.

While I have particularly shown and described the elements best adapted to perform the functions set forth, it will be understood that various changes in form, proportion and in the minor details of construction may be resorted to, without departing from the spirit or sacrificing any of the principles of the invention.

What I claim is:

1. In an homogenizer structure, a chamber having inlet and outlet means therefor, a valve seat provided with a passage communicating with said inlet means, a substantially cylindrical valve adapted for abutment with said seat, the outer end of said valve having a cup-shaped recess therein, means for manually adjusting said valve with respect to said seat including a thrust bearing fitting within the recess, and an alining disk in the recess interposed between the thrust bearing and the inner end of the recess and cooperating with the thrust bearing and the annular wall of the recess to maintain the valve in alinement with respect to its seat.

2. In an homogenizer structure, a chamber having inlet and outlet means therefor, a valve seat provided with a passage communicating with said inlet means, means for feeding material to said passage, a valve adapted for abutment with said seat, said valve being substantially cylindrical and having a recess in the outer end thereof, the walls of said recess having tapered inner end portions, means for adjusting said valve with respect to the seat including a thrust bearing snugly received in the outer portion of the recess, and a tapered disk in the tapered inner portion of the recess abutting the bearing and cooperating with the bearing and the walls of the recess to self-align the valve with respect to said seat.

3. In a homogenizer structure, a housing defining a chamber having a peripheral wall and inner and outer side walls, the inner side wall having an inlet, an annular valve seat carried by the inner wall about an inlet, a sleeve extending outwardly from the outer wall about an

opening opposite the valve seat, a packing encircling the opening, a block snugly fitting within the sleeve through the outer end thereof and extending through the opening into the chamber in alignment with the valve seat, said block having its inner end shaped to form a valve for seating against the valve seat and its outer end portion formed with a concentric pocket having a tapered inner end portion and a flat inner

end wall, a tapered disk filling the tapered inner end portion of the pocket and conforming to the taper thereof, a cap fitting about said sleeve in threaded engagement therewith, and a thrust bearing mounted in the cap concentric thereto and extending into the outer end of the sleeve and snugly fitting within the pocket in flat face to face abutting engagement with the disk.

JOHN MARCO.
